(57) **CLAIM**

The ornamental design for an enteral nutrition bag, shown and described.

DESCRIPTION

FIG. 1 is a front view of the enteral nutrition bag showing our new design;

FIG. 2 is a back view thereof;

FIG. 3 is a top plan view thereof;

FIG. 4 is a bottom plan view thereof;

FIG. 5 is a right side view thereof;

FIG. 6 is a left side view thereof; and,

FIG. 7 is a perspective view thereof.

The broken line showing of parts of the drawings is included for the purpose of illustrating use and environment and forms no part of the claimed design.
